COLLAR PIN WITH CONTROL MEANS

Anthony Dovica, Los Angeles, Calif.

Application May 12, 1949, Serial No. 92,803

7 Claims. (Cl. 24—87)

1

This invention relates to a pin for detachably connecting the front ends of a soft collar beneath the knot of a necktie.

It is an object of the invention to provide such a pin adapted to engage the under layer only of a double fabric layer collar and thus to center the tie knot between the ends of the collar without penetrating the outer layer of collar fabric.

It is a further purpose to provide such a pin particularly adapted to gather and retain at each end thereof, a predetermined quantity or length of fabric in a manner that securely anchors the pin without endangering tearing of the fabric along the line of the pin.

Another object is to provide such a pin assembly combining a fabric-supporting base plate and transversely extending baffle or limit means at the bend of the pin.

Yet another purpose is to provide such a pin having a self-acting fabric-engaging portion closely adjacent the pin point for yieldingly holding the length of fabric pierced by the point and run up against the terminal baffle, as well as having the point raised therefrom to a guide position for allowing the pierced fabric to pass easily therebeneath.

Still other features comprise the provision of such a plate having means for centering and anchoring the pin thereon in assembly; in one embodiment the plate is so shaped that only the terminal bending of the pin is required while effecting two different spacings of the bent portion of the pin from the base plate which it overlies.

Other objects and advantages of the invention will be apparent from the following description and claims, the novelty consisting in the features of construction, combination of parts, the unique relations of the members and the relative proportions, disposition, and operation thereof, all as more completely outlined herein and particularly pointed out in the appended claims.

In the drawings, which form part of the present specification:

Figure 1 is a front view of a soft collar and necktie, showing my collar pin in place;

Figures 2 and 3 are side and front elevational views respectively of one end of one form of my collar pin, the former showing it attached to one end of a collar;

Figures 4 and 5 are side elevation and perspective views respectively of another form of my collar pin, the former showing it attached to one end of a collar;

Figures 6 and 7 are side elevation and perspective views respectively of still another form of my collar pin, the former showing it attached to one end of a collar.

In Figures 2 thru 7, only one end of my collar

2

pins is shown, it being understood that the opposite end is identical. As seen in Figure 1, my pins are of the type comprising an arcuate or outwardly bowed stem 10 adapted to lie beneath a necktie 12, while an inturned pin on each end engages the adjacent end of a collar from beneath so as to prevent separation of the two ends 14, 16 of the collar beyond their desired position along the adjacent sides of the tie. The bow 10 simultaneously supports the tie knot from beneath in a slightly forward position and thus serves to anchor it in a central position between the collar ends. Such soft collars are made of two or three layers of material and the engaging pin on each end of my bow 10 is adapted by the present construction to penetrate and attach itself only to the under layer 18 or layers of collar fabric (Figs. 2, 4, 6) so that it is not visible from the outside.

In the form shown in Figures 2-3, there is provided a substantially flat, generally rectangular plate 20, soldered, welded or otherwise attached to the stem 10 along its under face and having a central transverse notch 22 at its outer end along which the stem is turned up at 24 and then bent back on itself at 26. On this somewhat resilient, bent-over portion 26 there is slid a centrally apertured, spherical ball 28 which is similarly secured to the plate 20 and/or the upturned length 24. Inward from the ball, the pin is bent down at 30 to normally overlie the plate by somewhat less than the thickness of one layer of fabric 18, terminating in a slightly elevated point 32 adjacent the inner edge of the plate 20. The elevation of the point 32 is thus sufficient only to penetrate the inner 18 layer or layers of fabric and not enough to go thru the outer or face layer 19. By this construction, the point 32 going thru the rear layer of collar fabric allows a length 40 of cloth—a measured amount—to gather in the space between the bend 30 and ball 28 with the pierced end turned up to rest in abutment against the ball which thus serves both as a stop or anchor and a transverse barrier to prevent tearing of the fabric along the line of the pin. It will be appreciated, of course, that in mounting the collar pin, after one collar end (14) is secured, the opposite end (16) is drawn toward it a small amount before inserting the point 32 therein, so that the collar subsequently drawing back this distance, acts to slide the pierced fabric along the plate 20. Further, the depressed portion 30 cooperates to hold the fabric layer 18 at such point of compression or frictional engagement.

In the embodiment shown in Figures 4-5, there is provided a stepped plate 34 of generally triangular, inwardly converging shape. Near the apex of the triangle, the plate is turned back 60 perpendicularly at 36 with a rearward opening,

locating notch 38 therein to receive the stem 10. Moving outward, the raised portion 40 of the plate is succeeded by a sunken part 42, the further end of which is turned up in a terminal baffle or wall 44 having a central aperture 46 therethru. By use of this construction the pin can be bent to its final shape before assembling with the plate. The stem 10 is turned up at 48 and then brought back in a straight line 50 parallel to the stem 10 to terminate in a point 52 10 which overlies the step 40, spaced thereabove by the approximate thickness of a layer of fabric 18. The bent stem thus has its return arm 50 inserted thru the hole 46 with its portion 48 in abutment with the outer face of the wall 44 and with the stem 10 disposed in frictional engagement with the underface of the sunken part 42. In this position, the plate and pin can be secured together as by filling the space 54 with solder or the like. It must accordingly be apparent, again, that a measured amount of fabric can be accumulated and anchored in the space between the staple 50 and the bottom of the trough 42 and due to being turned upward to pass over the baffle 44 it is protected against tearing along the line of piercing.

A still further modification is illustrated in Figures 6-7 wherein the triangular plate 56 contains only one bend to form the perpendicular end wall 58 which is provided with a centered hole 60 thru which the staple arm 62 is inserted and then bent down near the point 64 so as to closely overlie the plate as in the preceding form of Figures 2-3. Again, the curve 65 resiliently presses the inner layer or layers of material against the plate. The rear face of the plate 56 is soldered or otherwise secured to the adjacent stem and for the purpose of locating the latter therealong, the plate may be provided with a shallow longitudinal groove for alignment of the two. Again, it will be apparent that the space 66 between the staple 62 and plate 56 will receive and retain a predetermined length of the material.

Thus it will be seen that I have provided a basic construction for collar attachment pins which is both highly efficient in use and comparatively simple in fabrication and assembly. This is a continuation-in-part of my pending application "Pin for Dress Shirt Collars," Serial No. 28,151, filed May 20, 1948, now abandoned.

While I have shown and described in some detail a presently preferred embodiment of my collar pin, it is to be understood that various modifications may be made in the construction and operation thereof within the spirit and scope of the subsequently claimed invention which it is my intention to claim broadly within the limitations imposed by the prior art.

I claim:

1. A collar pin of the character described comprising: a generally arcuate stem, each end of which is bent back on itself and brought to a point over the convex face of the stem, a transverse plate secured to the stem within each bent portion, and transversely extending limit means secured along each plate at the point of bending of said stem and projecting from said stem outward in all directions so as to frictionally resist any further movement by the stem through the fabric after piercing a layer of fabric and being pulled until said limit means are adjacent the

point of penetration of the fabric, the bent portion of the stem being spaced from said plate adjacent its point approximately the thickness of a layer of fabric and thence spaced farther apart from said plate so as to prevent said fabric from being tightly wedged between the stem and the plate, thereby facilitating its ready withdrawal.

2. The collar pin of claim 1 wherein said plate is substantially flat and said limit means comprise a substantially perpendicular, forward-extending wall along its outer edge.

3. The collar pin of claim 1 wherein said plate is substantially flat and said limit means comprise a substantially perpendicular, forward-extending wall along its outer edge, said wall being traversed by a hole to receive the bent portion of the stem therethru.

4. The collar pin of claim 1 wherein said plate contains a raised step adjacent the point of the stem and underlying the same and said stem is substantially straight from its terminal bend to its point.

5. The collar pin of claim 1 wherein said limit means comprise an apertured ball secured to the plate adjacent its outer edge with the bent portion of the stem inserted thru the ball.

6. A collar pin of the character described comprising: a generally arcuate stem, each end of which is bent back on itself and brought to a point over the convex face of the stem, and a transverse plate secured to the stem within each bent portion, the inner end of the plate forming a bridge, the top of which is spaced below the adjacent point end of the pin by less than the thickness of a layer of collar fabric, the inner end of the bridge being turned down and provided with a centering notch to receive the stem therein, and the outer end of the bridge descending into a trough portion which at its further end is turned up to form a wall having a hole thru which the pin point is inserted upon assembly.

7. A collar pin of the character described comprising: a generally arcuate stem, each end of which is bent back on itself and brought to a point over the convex face of the stem, and a transverse plate secured to the stem within each bent portion, the outer end of the plate being turned up to form a wall having a hole near its outer edge thru which the pin point is inserted upon assembly, said pin being thus spaced above the plate after insertion thru the hole and then bent down adjacent its point so as to overlie the plate by less than the thickness of a layer of collar fabric, said point then being raised slightly to allow easy passage therebeneath of said thickness.
